UNITED STATES PATENT OFFICE

CHARLES M. GRAVATT, OF ASHEVILLE, NORTH CAROLINA

DESIGN FOR A GAME APPARATUS

Application filed September 14, 1932. Serial No. 44,831. Term of patent 3½ years.

To all whom it may concern:

Be it known that I, CHARLES M. GRAVATT, a citizen of the United States, and resident of Asheville, in the county of Buncombe and State of North Carolina, have invented a new, original, and ornamental Design for a Game Apparatus, of which the following is a specification, reference being had to the accompanying drawing, forming a part thereof.

The figure is a view in perspective of a game apparatus showing my new design.

I claim:

The ornamental design for a game apparatus, substantially as shown.

Signed at Asheville, in the county of Buncombe and State of North Carolina, this 9th day of September, A. D. 1932.

CHARLES M. GRAVATT.
